UNITED STATES PATENT OFFICE.

HARRY ANDERSON, OF HADDONFIELD, NEW JERSEY.

AUTOMATIC FIRE-ALARM BOX.

No. 917,235.

Specification of Letters Patent.

Patented April 6, 1909.

Application filed October 6, 1908. Serial No. 456,449.

To all whom it may concern:

Be it known that I, HARRY ANDERSON, a citizen of the United States, residing at Haddonfield, in the county of Camden and 5 State of New Jersey, have invented certain new and useful Improvements in Automatic Fire-Alarm Boxes, of which the following is a specification.

This invention relates to certain new and 10 useful improvements in automatic fire alarm boxes, such as are operated by electrical connection with a thermal circuit closer of the general type shown in my application for patent, Serial Number 415,948, and which 15 have electrical connection with a central station for sounding a gong thereat a number of times corresponding to the number of the thermal circuit closer station.

Reference will be had to the accompanying 20 drawings forming a part of this specification and wherein like characters of reference designate corresponding parts throughout the several views, in which:

Figure 1 is a side elevation with a section 25 of the casing removed, Fig. 2 is an elevation of the opposite side, a section of the casing being removed, Fig. 3 is a top plan view partly in section, with the cover removed and illustrating the wiring of the various 30 circuits, and Fig. 4 is a vertical section taken on the line 4—4 of Fig. 3 and looking in the direction of the arrows.

Reference numeral 1 designates the casing provided at one end with binding or terminal 35 posts 2, 3 and 4, and at the other end with posts 5 and 6. At opposite ends of the box or casing are switches A and B.

Reference letter C indicates the thermal circuit closer, or in fact, any circuit closer 40 adapted to act automatically in case of fire, and D and E indicate two sets of batteries, two cells to the set.

The battery set D is connected at one end with the thermal circuit closer C and the binding 45 post 3 and through wire 3' with one terminal of the motor M. The other end of the battery set D connects with the binding post 6 from which wire 6' leads to the said switch B and from thence through wire 6'' to the binding 50 post 5. A wire 5' connects the said post 5 with the lower adjustable contact screw 7 of an automatic circuit-breaker G. The upper adjustable contact screw 8 of the circuit-breaker G is carried by the free end of a lever 55 arm 9 pivoted at 10 to a block 11 insulated by element 12 from the metal frame 13. The

said screw 7 is mounted in a bracket 14 together with an extension 15, and the said parts 7, 14 and 15 are insulated from each other as illustrated. To the free end of the lever arm 9 and to the said extension is connected a coil spring 16 for holding the lever arm normally depressed. The lever arm 9 is provided with a cam finger 17 insulated therefrom and which is adapted to be engaged by a loose cam lever 18 to lift the said arm 9 upon every revolution of the wheel 19, the movement of the loose lever 18 being limited by stops 20 provided on the wheel 19. The aforementioned circuit from battery set 70 D is completed to the other terminal or motor M through wire 11' connected with the said block 11. Pivoted in a block 21 insulated from the casing 13 is a pawl 22 provided with a ledge 23 and this pawl is normally 75 pressed into the path of the movement of lever 9 by a spring 24, as illustrated in Fig. 3. The screws 7 and 8 normally contact as in Fig. 2 to complete the motor circuit with battery set D in event thermal circuit closer C 80 becomes closed. In case of fire, this circuit closer will become closed and the motor M will thereby be caused to operate and through suitable gearing, to be described, will cause the wheel 19 to rotate. Upon one complete 85 revolution of the said wheel 19, the loose lever 18 thereof will contact with the finger 17 of the lever arm 9 thereby raising the lever arm 9 and breaking the electrical circuit at G, causing the motor M and consequently the 90 wheel 19 to stop. While the lever arm 9 is in this raised position, the pawl 22 will be sustained on the ledge 23 of the pawl until the device is reset. It will be noted that when the motor M stops, due to breaking of 95 circuit at G, that the wheel 19 stops before the loose lever 18 passes or trips the finger 17. Resetting consists in restoring thermal circuit closer C to normal open position, manually lifting lever arm 9 and moving loose lever 18 from beneath finger 17 as in Fig. 2, and in forcing the pawl 22 to position out of path of arm 9 to permit the said arm 9 when released to fall under tension of spring 16 to close the automatic circuit breaker G. The 100 casing 1, as illustrated in Fig. 3, is provided with an opening 22' closed by wicket 22'', to permit access to interior of the box.

The gearing, aforementioned, for operating the wheel 19 consists of a shaft 25 on which 110 said wheel 19 is mounted, and on this shaft 25 is a large gear 26 meshing with smaller

5 gear 27 on shaft 28. A large gear 29 is also secured to the shaft 28 and is operated by a small gear 30 on shaft 31 to which latter is secured a large gear 32 operated by worm 33 on the motor shaft 34. The shafts 25, 28 and 31 are journaled in the metal frame 13.

Secured to the outer end of the shaft 28 is a counting wheel 35, and attention is here directed to the fact that this counting wheel, 10 owing to the gears 26 and 27, turns several times around to the single rotation of the wheel 19, to enable the alarm to be sounded a number of times before the trip lever 18 of the wheel 19 raises the lever arm 9 to break 15 the motor circuit at G.

The battery set E, (see Fig. 3) is in circuit with the binding post 4 and the other end is in circuit with a gong F or other alarm and with the binding post 2. The binding post 2 20 is in electrical connection through wire 2' with the lower adjustable contact screw 36 of the closer H, (see Fig. 1). The binding post 4 is connected by wire 4' with the switch A from which the circuit is completed 25 by wire 4" with the bracket 37 insulated from the metal frame 13. Journaled in this bracket by means of a pin 38 are two arms 39 and 40 constructed to move together, the arm 40 being insulated by collar 41 from the 30 other parts and out of circuit, and the arm 39 being in circuit with the bracket 37 and carrying the upper adjustable contact screw 42. These contact screws 36 and 42 are normally 35 drawn toward each other by coil spring 43 attached at one end to the insulated bracket 44 of the upper contact screw and at the other end to the bracket 45 of the lower stationary contact screw 36, which latter is mounted in and insulated from a bracket 46 of the metal 40 frame 13, but also insulated from the same.

During the rotation of the wheel 19 as previously described, the counting wheel 35 will rotate a number of times, as desired or rather as geared, and as the end of the arm 40 falls 45 into the notches 35' of said wheel 35, the arm 39 will be lowered thereby causing the contact screw 42 thereof to engage the contact screw 36 of circuit closer H to close the gong circuit and sound the gong F a number of 50 times corresponding to the number of notches in the counting wheel 35.

To test the box, open switch A and then close switch B, and let the box run until the motor circuit is broken at G, which will take 55 about two minutes, then lift lever arm 9, pull loose lever 18 in wheel 19 forward or to position illustrated in Fig. 2, push pawl 22 back, which closes circuit breaker, then turn switch B off and switch A on and box is 60 ready for work.

Having fully described the invention, what is claimed as new and useful and desired to be secured by Letters Patent, is:

1. In a device of the character described, 65 a motor, an alarm mechanism involving two

contact members, means operated by the motor during operation of the alarm mechanism for moving one of said contact members from engagement with the other to break the motor circuit, and means for positively locking said contact member in said disengaged position. 70

2. In a device of the character described, a motor, an alarm mechanism involving two contact members, means operated by the 75 motor during operation of the alarm mechanism for moving one of said contact members from engagement with the other to break the motor circuit, and a pawl for automatically locking said contact member in 80 said disengaged position.

3. In a device of the character described, a motor, a circuit breaker comprising two contact members, means continuously movable by and during operation of the motor 85 for operating one of the contact members, said means being capable of independent movement.

4. In a device of the character described, a motor, a circuit breaker involving a movable contact member, normally rotatable means operated by the motor for operating said contact member, said means being capable of independent movement in the direction of its travel after operation of said contact member. 90

5. In a device of the character described, a motor, a circuit breaker involving two contact members, means continuously movable by and during operation of the motor and 100 being adapted to engage one of the contact members to disengage it from the other, said means being capable of being moved out of engagement with the first contact member independently of the motor, and means for 105 positively engaging and locking said first contact member in disengaged position.

6. In a device of the character described, a motor, a motor circuit breaker involving a movable contact arm, a shaft rotatable by 110 means of said motor, a cam member continuously movable with the shaft for moving the contact arm into cut-out position, said cam member being capable of independent movement on the shaft. 115

7. In a device of the character described, a motor, a circuit breaker involving a movable contact member, a shaft rotatable by means of said motor, an arm loosely mounted on the shaft and being capable of independent concentric movement, means carried by the shaft for causing said arm to move therewith to move said contact member to open position, and automatic means for engaging said member to hold the same 120 in open position after independent movement of said arm. 125

8. In a device of the character described, a motor, a circuit breaker involving a movable contact member, a shaft rotatable by 130

said motor, an arm loosely mounted on said shaft, means for continuously rotating the arm with the shaft said arm being capable of movement on the shaft independent of 5 said means.

9. In a device of the character described, an alarm mechanism, a motor for operating the same, a normally open contact and a normally closed automatic contact device in 10 the motor circuit, means operated by the

motor for breaking the closed contact to stop the motor after sounding the alarm mechanism.

In testimony whereof I affix my signature in presence of two witnesses.

HARRY ANDERSON.
